UNITED STATES PATENT OFFICE.

JAMES BAILEY SCHOGGEN, OF MOUNTAIN HOME, ARKANSAS.

CHURN.

SPECIFICATION forming part of Letters Patent No. 296,630, dated April 8, 1884.

Application filed January 11, 1883. (No model.)

To all whom it may concern:

Be it known that I, JAMES BAILEY SCHOGGEN, a citizen of the United States of America, residing at Mountain Home, in the county of Baxter and State of Arkansas, have invented certain new and useful Improvements in Churns, of which the following is a specification, reference being had therein to the accompanying drawings.

10 My invention relates to churning; and it consists in the parts which will be hereinafter described, and pointed out in the claim.

In the accompanying drawings, Figure 1 represents a front elevation of the device, 15 showing the dashers in dotted lines. Fig. 2 is a side elevation, also showing the dashers in dotted line. Fig. 3 indicates a plan view of the milk-vessel and its cover. The first view shown under Fig. 4 represents a cross-section through 20 one of the side guide-plates. The second view under said figure is a cross-section through the face-plate which secures the horizontal bar that connects the cranks. Fig. 5 is a detail showing two perforated dashers at the 25 bottom of a rod.

Similar letters indicate similar parts throughout the several views.

The letter A represents the vessel or churn proper, and A' the cover for the same.

30 a a are two openings in said cover.

B B are two semicircular perforated dashers secured to the bottom of vertical rod C. The upper ends of the rods C engage the openings E of the pitman-rods F, and are secured thereto by means of set-screws D. The two rods C F can be detached and the upper operative parts disunited from the lower parts or churn proper.

F' is the top of rod F, at which point rod 40 G is pivoted thereto. The lower end of rod G fits over the handle-bars.

H is a crank-piece, and I a wooden handle on the handle-bar.

J J are the face-pieces of the side guide- 45 plates for the rods F.

J' are the under pieces, and J² the circular opening formed by the union of plates J and J'.

j j are bolts uniting the plates and securing 50 the same to the block, which will be herein-after described.

K and K' are face-plates securing the crank-shaft to the block L. Said crank-shaft works in the opening K².

k k are bolts uniting the plates, and by means 55 of which said plates are secured to the block.

L represents a rectangular block of wood, which is extended out from the wall and secured in a fixed position by means of the stays M.

N are the bolts uniting the front arms, M², of the stay to the block. The back pieces or arms, M', of the stay M rest against the wall and are secured thereto by any suitable means.

The letter O indicates the wall. 55

The device is operated by a person turning the cranks. The most convenient way is to sit immediately in front and operate the cranks by both hands. It is obvious, however, that the machine can be worked with 70 one hand and from any accessible point, and that power given to one crank is communicated to the opposite handle, and all the parts thereby operated. This is accomplished inasmuch as the several parts of the handle are 75 all rigidly united and formed of a single piece.

By adding an extra dasher to each rod, I am enabled to increase the agitation of the liquid and expedite the formation of butter.

I attach importance to the fact that the 80 stay M is secured to the block L at one end, while its inner portion is attached to a wall of a room, or any other suitable place, whereby the mechanism is held in position while in operation, and the dasher-rods C adapted 85 to be removed from the pitman-rods F for the purpose of cleaning the churn without detaching said stay from its fastening.

I am aware that the mechanism hereinbefore described is old, and I do not claim such 90 as my invention; but

What I do claim is—

The combination of the mechanism herein described with the block L, having the stay M, composed of the arms M' M², for attaching the mechanism to any suitable place, whereby the churning-vessel and its dashers are adapted to be removed therefrom, as shown and described. 95

In testimony whereof I affix my signature in 100 presence of two witnesses.

JAMES BAILEY SCHOGGEN.

Witnesses:

JAMES M. SCHOGGEN,
JOHN S. RUSSELL.
